UNITED STATES PATENT OFFICE.

BENJAMIN W. TUCKER, OF SOUTH ORANGE, NEW JERSEY, ASSIGNOR TO CORONA TYPEWRITER COMPANY, INC., A CORPORATION OF NEW YORK.

TYPE-WRITING MACHINE.

1,281,101.

Specification of Letters Patent.

Patented Oct. 8, 1918.

Original application filed February 21, 1914, Serial No. 820,244. Divided and this application filed December 4, 1915. Serial No. 65,034.

To all whom it may concern:

Be it known that I, BENJAMIN W. TUCKER, a citizen of the United States, and a resident of South Orange, county of Essex, and State of New Jersey, have invented certain new and useful Improvements in Type-Writing Machines, of which the following is a full, clear, and exact description.

This invention relates more particularly to foldable, visible or front strike typewriting machines, and is a division of my application Serial No. 820,244, filed February 21, 1914.

One of the principal features of the present invention is to provide a typewriting machine in which an inclosing case forms the frame and support for the mechanism and parts of the typewriter and which is of such a construction that a standard or universal keyboard may be mounted thereon to operate the usual typewriter mechanism and when not in use the cover of the case or support with the keys including the key parts of the spacing and case shift mechanisms may be folded upward to make the machine compact and to adapt the mechanism to be inclosed within the case.

Another object of the invention is to provide a universal keyboard including the spacing and case shift means a part of which may be mounted upon a foldable member forming a part of the inclosing case or as a part independent of the case.

A further object of the invention is to provide a construction wherein the key-operated levers of a universal or standard keyboard are mounted upon a common fulcrum support which serves also as a pivot for the folding movement of all of the keys of the keyboard, and which permits a positive connection to be maintained between the parts operated by the keyboard and the keyboard itself, and which mechanism may be mounted directly on or within the case or in a skeleton frame in which the parts may be assembled and mounted within the case so as to form a permanent part thereof or in a frame which is adapted to be placed within the usual carrying case.

Other objects of the invention are to provide a case forming a support for the parts of a typewriting machine; to provide a case

which is so constructed that the entire mechanism may be inclosed within the case; to provide a case and support which will permit the keys of a universal keyboard to be folded upward and inward so as to substantially overhang the type-bars or platen carriage of the machine, and to be located within the case when not in use; and to provide a light, portable and compact machine which may be readily carried by a person as a part of his luggage.

A still further object of the invention is to provide a key action of a foldable character wherein the type-bars may be given either a pull or a push action during the printing movement of the type.

A still further object of the invention is to provide a key action which is simple in construction and in which the key-operated levers comprise substantially two parts or levers mounted upon a common support and parts of the key-lever or key-operated levers connected together in such a way that on the depression of a key both parts will be operated, but which permits the key with one part of the key-operated lever to be folded to an inoperative position to make the machine compact.

With these and other objects in view, the invention will be hereinafter more particularly described with reference to the accompanying drawings, which form a part of this application, and will then be pointed out in the claims at the end of the description.

In the drawings, Figure 1 is a plan view of one form of machine embodying the invention, showing a construction wherein the cap, cover, or top section of the case is hinged at the rear, and the keyboard support or member hinged or pivoted at the front to adapt the latter to be folded upwardly and rearward and to be inclosed within the cover.

Fig. 2 is a side elevation of the machine in position for use, the top or cover being partly broken away and showing in dotted lines the position of the cover and keys when the machine is compact.

Fig. 3 is a vertical transverse section of the key action and certain parts of the mechanism of the machine, other parts of the machine being removed.

Fig. 4 is a detail enlarged section of one

of the key-operated levers in position for use.

Fig. 5 is a similar view showing the key and a part of one of the key-operated levers 5 moved to a folded position.

Fig. 6 is a rear elevation of one of the key levers in a depressed position.

Fig. 7 is a section similar to Fig. 4, except that the key has been depressed.

10 Fig. 8 is a view somewhat similar to Fig. 2, showing the key action modified so that on the depression of a key the type-bar is moved with a pull action instead of a push action as in Figs. 1 and 2.

15 The case 10 may comprise a main member 11 and a top member 12, the latter being hinged at 13 to the main member 11 at the upper and rear edge thereof, and is adapted to be moved forward over the main mem-

20 ber 11 on the hinge 13 to the position shown in the dotted lines in Fig. 2, so as to make when closed a regular and substantially uniform box-like package.

A support or fulcrum rod 14 extends 25 transversely of the machine and at its ends is mounted in brackets 15 in which latter the said rod may be held by screws 16 or in any other desired way. A keyboard frame or support 17 of a substantially U-shaped con-

30 struction is pivotally mounted upon the rod 14 in such a way that it may be unfolded to the position shown in full lines in Figs. 1 to 3, or may be folded upwardly and rearward to the position shown in dotted lines in Figs.

35 2 and 3, said keyboard frame or member being held when in a normal working position substantially horizontally. The rod 14 has mounted thereon a number of levers 18. These levers 18 comprise two parts 18^a and 18^b. The part 18^a is provided with a key 19 at one end thereof, and is normally retained in one position by a spring 20 one end of which is attached to the part 18^a and the other end to a transversely extending bar

40 21, said bar 21 extending between the sides of the keyboard frame or member 17. The part 18^a has a substantially U-shaped portion 22 having parts thereof provided with apertures and through which the rod 14

45 passes so as to provide a substantial bearing for the key-operated part 18^a. This part 22 is provided with an extension or projection 23 which is adapted to engage an extension or projection 24 of the key-operated part

50 18^b when the key 19 is depressed and moves the part 18^b on the pivot rod 14 as shown best in Fig. 7. The extension 24 is formed on a substantially U-shaped part 25 of the lever part or member 18^b and said part 25

55 fits about the part 22 to permit the latter to move within the same, said part 25 having apertured parts through which the rod 14 passes and which parts are connected by a tie-bar, as 25^a, and provide a substantial

60 bearing for the part or member 18^b. The le-

ver parts or members 18^a while substantially positively connected with the parts 18^b, and for all practical purposes are positively connected when in operative position, still the knuckle or knee-joint connections between the two permit all the parts 18^a of the key-operated levers to be folded upwardly and rearward with the keyboard frame or member 17 out of operative connection with the parts 18^b as shown in dotted lines in Figs. 70 2 and 3. The levers are arranged in banks or groups as 26, 27 and 28, this number varying according to the number of key-operated levers employed and whether or not a single or double case shift is employed. The parts 80 or levers 18^a of the different groups are under this construction of different lengths to adapt the keys to be positioned properly, and the parts or levers 18^b of the key-operated levers may be also of different lengths, 85 so that the same force will be required to depress the keys of the different groups and in this way a substantially uniform touch is obtained.

Each key-operated lever part or lever 18^b 90 is connected by a link 29 to a projecting portion, as 30, located at the inner and under part of a type-bar 31, there being a type-bar for each link and for each two-part key-operated lever. The type-bars 31 are pivoted at 32 to hangers 33 or to a segment as preferred, and at their outer ends are provided with type blocks or heads 34 on each of which are type representing upper and lower case characters and figures according 100 to whether a single or double case shift is employed. The type-bars are arranged in the usual curved path and are supported at their outer ends on a cushion 35 mounted upon a curved plate or device 36, and are 105 adapted when the keys 19 are depressed to be forced outwardly and rearward against a platen 37 mounted upon a platen carriage 38. The type-bars as well as the key-operated lever parts 18^b are restored to their normal position by means of springs 39, one end 110 of each spring being attached to one of the links 29 and the other end to a transversely extending bar 40 for the shorter lever parts, or by springs 41 one end of each of which 115 is attached to each of the longer parts of the key-operated levers and the other end of said springs to a transversely extending bar 42.

A space bar 43 is mounted upon the outer 120 ends of two two-part space levers 44. The space levers 44 are pivotally mounted upon the transversely extending pivot rod 14 and have knuckle or knee joints between the two parts thereof of the same construction as 125 the key-operated levers 18, said spacing levers having one part thereof bent at an angle as at 45 so as to extend from the inner portion thereof outward and in such a way as to be mounted upon the rod 14. Each 130

space lever is connected by a link 46 to an arm 47 of a lever 48. Each lever 48 is mounted upon a transversely extending rod 49 and has one arm as 50 connected to one 5 end of a spring 51, the other end of said spring being held to a transversely extending bar 52. Each lever 48 has an arm 53, the inner portion of which is forked, as at 54, and in the forked end of each lever is located the universal bar 55. This universal bar is operated by the levers 48 as the space-bar 43 is operated and by a projecting part 55^a on each type-bar as each key 19 is depressed. The universal bar is connected by 10 arms 56 to bell-crank levers 57, said bell-crank levers being adapted to operate a rocker frame 58. This rocker frame 58 is adapted to operate a suitable escapement mechanism, not shown, and suitable ribbon mechanism both for feeding the ribbon lengthwise and for vibrating the ribbon to cover and uncover the printing point or to permit the ribbon to remain inactive for stenciling purposes. The escapement mechanism, the ribbon mechanism and the particular parts for operating these features by which the carriage is given a letter-spacing movement and by which the printing is effected in visible writing machines may be 15 of the usual or of any preferred construction and form no part of the present invention, it being understood that the carriage is suitably mounted to travel transversely of the machine upon a support as 20 59 or otherwise and controlled by the escapement mechanism during its letter-spacing movement. As the space bar 43 is moved it will operate the links 45, and these links will operate the levers 48 and 25 through the latter move the universal bar by which the escapement is tripped and the carriage moved a letter space in the usual way.

The support 59, forming the bed for the 30 platen carriage 38, is adapted to be given a vertical movement to adapt the type heads to have a plurality of characters thereon. As shown the support 59 is held to slides or posts 60 mounted to move vertically at the 35 rear right and left portions of the main member 11 and suitably guided thereon. An arm 61 is connected to each slide or post 60 at one end and at the other end is held to the rod 49. An arm 62 is operatively 40 connected to one or both of the arms 61 and said arm 62 or each of them is connected by a link 63 to a part 64 of a platen shift lever 65. There are two platen shift levers 65 and 66, each of which is provided with a 45 key 67 and each platen shift lever is formed in two parts. The parts of the platen shift lever are mounted upon the transversely extending rod 14, and are foldable with respect to each other as is the case with the 50 key-operated levers, and are constructed

with a knuckle or knee-joint connection to adapt one part to fold with respect to the other or to cause the two members or parts of the levers to operate in unison when in normal operative position as already described. The platen shift levers are constructed to move the support 59 and carriage relatively different distances by means of suitable stops or otherwise and may be locked in their depressed position by a single 70 locking lever 68 one end of which is adapted to engage notches of each of said levers. The shift mechanism as well as the letter spacing mechanism described is not shown in detail and forms no part of the present 75 invention, except so far as the two-part levers form a part of the universal or standard key-board and so far as their mounting upon the common rod 14 is concerned whereby a part of each shift and space lever may partake of the folding movement of the support or frame 17, though instead of a double case shift it is to be understood that a single platen or type case shift may be employed.

It will be evident that the rod 14 forms the pivot for the support 17 and for the space levers, key-operated levers for the type, and the shift levers, and the pivots therefore, of all these parts are in alinement. It will be evident further that by reason of the knee or knuckle joint connection between the two-part levers for the type, the platen shift and the spacing means, one part of each of said levers, for example, that part which extends forward, is adapted to fold upwardly with the keyboard frame 17 so that all those parts that project beyond the member 11 of the case may be made to extend inward over the type-bars in close relation to the platen carriage. When the 90 cover or top section 12 is in the position shown in dotted lines in Fig. 2 the case will entirely inclose the keys and the keyboard frame 17, said cover 12 being provided with an extended portion, as 69, by which the 95 opening in the front of the case may be closed, there being suitable clasps as 70 to hold the extended portion 69 as well as the top section in its closed position. When in the closed position the case may be readily 100 transported and for this purpose a handle as 71 shown in dotted lines in Fig. 2 may be provided to serve as means to carry the case.

In Fig. 8, the construction is substantially 105 the same as shown in Figs. 1 to 7 except that auxiliary levers 69^a are connected by links 70^a to arms 71^a operated by the key-levers and spacing and shift levers. The levers 69^a at their lower ends are connected by links 72 so that instead of a push action being given to the type-bars, the said type-bars have a pulling action given thereto through the links 72.

From the foregoing it will be evident that 110

simple and efficient means is provided whereby a simple and efficient foldable visible typewriting machine is provided which has means for mounting the parts of the 5 keyboard upon a common fulcrum or pivot connection in such a way as to adapt the various mechanisms to be operated by the keys when the machine is in its normal operative or unfolded position; that no disorganization or manual disconnection of any 10 of the parts is required to fold or unfold the parts; that a machine embodying the foldable principle disclosed permits the machine to be made very compact; that all of 15 the parts of the machine may be inclosed in a carrying case which also forms a frame for the different parts of the typewriter, or the case may be independent of the supporting frame; and that said machine may 20 have its parts light yet strong to adapt the machine to be easily transported; and that said machine may be readily made and assembled.

Having thus described my invention, I 25 claim as new and desire to secure by Letters Patent:—

1. In a visible typewriting machine, the combination of a support comprising a plurality of sections hinged together to fold 30 and unfold, a platen carriage, type-bars, links connected to the type-bars, and keys pivotally mounted in alinement with the hinge of one of the sections to fold therewith and connected to said links.
2. In a typewriting machine, the combination of a support comprising a plurality of relatively foldable members, a platen carriage mounted on one member of the support, type bars maintained in normal operative relation to the carriage and mounted 40 on one of the support members, key levers one for each type-bar having a common mounting at a point coincident with the line of fold between two of the support members 45 and adapted to fold and unfold with one of said members, and means forming a connection between the type bars and key levers.
3. In a visible typewriting machine, the combination of a support comprising a plurality of relatively foldable members, a platen carriage, type-bars maintained in normal operative relation to the carriage and having an upward and rearward movement, key-levers one for each type-bar 55 mounted on the same member of the support as the type-bars and connected to fold with another member of the support, and means forming a connection with the type-bars and the key-levers.
4. In a visible typewriting machine, the combination of a platen carriage, a two-part support comprising a main member and a front member hinged to the main member to fold upward and over the same, type- 60

bars mounted on the main section, key-operated levers mounted on both members a part of which partake of the folding movement of the front member and means forming a direct connection between the type-bars and key operated levers. 70

5. In a visible typewriting machine, the combination of a foldable support, a platen carriage, type-bars maintained in co-operative relation to the carriage, keys one for each type-bar pivotally held on one part of 75 said support and foldable with another part of the support toward the platen carriage, and means forming a connection between each type-bar and one of the keys.

6. In a visible typewriting machine, the combination of a support, a platen carriage, type-bars having an upward and rearward movement and maintained in co-operative relation to the platen carriage, a universal keyboard having a two-part key-operated lever 80 for each type-bar one part of each lever being foldable with respect to the other and all having a common mounting, and means forming a positive connection between the type-bars and the key-operated levers. 90

7. In a visible typewriting machine, the combination of a support, a platen carriage, type-bars, a universal keyboard having a two-part hinged key-operated lever for each type-bar one part of which is movable into 95 compact relation with the platen carriage, and means forming a positive connection between the type-bars and the key-operated levers.

8. In a visible typewriting machine in 100 which the type-bars move upwardly and rearwardly, a frame having a main frame member and a foldable frame member hinged to the main frame member at the forward part thereof, two-part key-operated 105 levers pivotally held upon the main frame member and forming a part of a keyboard, and means whereby the key part of each key-operated lever will move the other part when in an unfolded position and which will permit the key part of said levers to fold with the foldable frame member and an inoperative connection with the means operated maintained. 110

9. In a typewriting machine, the combination of a foldable support, a platen, type-bars movable toward and from the platen, and two-part hinged and pivoted key-operated levers operatively connected to the type-bars, one for each type-bar, one part 120 of all of the levers being movable with one member of the support while the other part of said levers remains in co-operative relation to the type-bars.

10. In a typewriting machine, the combination of a foldable support, a platen, type-bars movable toward and from the platen, and two-part hinged key-operated 125

- levers having a common point of support for both parts and operatively connected to the type-bars, one for each type-bar, the key part of all of the levers being foldable with 5 one member of the support while the other part of said levers remains in coöperative relation to the type-bars, said parts of the levers while connected being adapted to operate the type-bars by the keys only when 10 the keys are in an unfolded position.
11. In a typewriting machine, the combination of a support having a foldable member and a normally stationary member, type-bars, a rod supported in the normally 15 stationary member, key-operated levers mounted upon the rod and operatively connected to the type-bars, one for each type-bar, said levers having two parts one of which remains in coöperative relation to 20 the type-bars and the other part partaking of the folding movement of the support.
12. In a typewriting machine, the combination of type, a platen carriage, and two-part foldable key-operated levers all pivotally held upon a common support and in alinement, one part of each key-operated lever being foldable toward the platen carriage to an inoperative and compact position.
- 30 13. In a typewriting machine, the combination of type-bars, a platen carriage, and key-operated levers having a plurality of parts connected together to permit one part to fold with respect to another, and links 35 operatively connecting the type-bars and levers.
14. In a typewriting machine, the combination of type, a platen carriage, and key-operated levers having parts connected together in pairs to permit one part to fold to a compact position with respect to another, one part of each lever being operatively connected to move a type.
- 40 15. In a typewriting machine, the combination of type-bars, a platen carriage, and two-part key-operated levers having a common alined fulcrum about which the two parts move, said parts of each lever being relatively foldable and operably connected 45 in one position only, and means connecting each type-bar to one part of said levers.
- 55 16. In a typewriting machine, a support, type, a rod mounted on the support, and relatively foldable two-part key-operated levers movable about the rod as a pivot and operatively connected to the type.
- 60 17. In a typewriting machine, a platen carriage, upwardly and rearwardly moving type, key-operated levers hinged on a common support to permit the keys to fold toward the platen carriage, and links forming a direct connection between the type and said levers.
- 65 18. In a typewriting machine, the combination of type, a platen carriage, and foldable levers provided with keys and having a common alined support, said levers being operatively connected to the type and movable toward the type and movable toward the platen carriage to make the machine compact.
19. In a typewriting machine, the combination of a support having relatively foldable members, a rod mounted upon one of said members and forming a pivot for another member of said support, key-operated levers mounted upon said rod, each comprising two members, each having projections adapted to engage on the depression of a key to move both parts of the key-operated 75 levers in unison or to permit one part of each key-operated lever to be moved relatively to the other to an inoperative position, said key-operated levers being arranged in groups and the parts of the levers 80 being of relatively different lengths to adapt the keys to have a substantially uniform touch, a platen carriage, type, movable upward and rearward toward the platen carriage, and operative connections between the 85 type and the key-operated levers.
20. In a typewriting machine, the combination of a support having relatively foldable members, a rod mounted upon one of said members and forming a pivot for another member of said support, key-operated levers each comprising two members, each 90 mounted on the rod and having projections adapted to engage on the depression of a key to move both parts of the key-operated 95 levers in unison or to permit one part of each key-operated lever to be moved relatively to the other, a platen carriage, type, 100 and operative connections between the type and the key-operated levers.
- 105 21. In a typewriting machine, the combination of a support having relatively foldable members, a rod mounted upon one of said members and forming a pivot for another member of said support, key-operated 110 levers mounted upon said rod, each comprising two members, each having projections adapted to engage on the depression of a key to move both parts of the key-operated levers in unison or to permit one part of each key-operated 115 lever to be moved relatively to the other, a platen carriage, type, movable upward and rearward toward the platen carriage, and operative connections between the type and the key-operated levers.
- 120 22. In a collapsible typewriting machine, the combination of a platen carriage, a support for the carriage, type bars, a key action having a pivoted key-supporting arm for each type bar, each adapted to be folded relatively to its associated type bar to make the machine compact when not in use, a second pivoted arm for each type bar having the

- same pivotal point as its associated key-supporting arm and operable thereby when the key-supporting arm is in its unfolded position, and links forming positive connections between the type bars and said second pivoted arms. 60
23. In a collapsible typewriting machine, the combination of a support, type bars mounted on said support, a rod mounted 10 on the support and extending transversely thereof, and foldable two-part key-operated levers movable about the rod as a pivot to operate the type bars and positively connected with the type bars. 65
24. In a collapsible typewriting machine, the combination of a support comprising relatively foldable parts, a platen carriage supported on one of said parts, type bars mounted on the carriage-supporting part, 20 keys pivotally supported at points in alignment with the point of fold of another of said parts and foldable therewith, and means forming a permanently maintained mechanical operating connection between 25 the keys and type bars. 70
25. In a collapsible typewriting machine, the combination of a frame, a platen carriage supported thereon, upwardly and rearwardly movable type bars pivotally mounted 30 in the frame, a rod mounted in the frame and extending transversely thereof, a support pivotally held at its rear end to said rod and foldable upwardly and rearwardly toward the platen carriage, and a key action 35 comprising two-part levers all pivotally mounted on said rod and each having its parts connected by a hinge joint coincident with the pivotal point of the lever and said support, the forward parts of the levers being 40 of different lengths and supporting keys in banks and being foldable with said support to a compact position above the type bars, and means forming constantly maintained positive operating connections between 45 the rear parts of said levers and the type bars. 75
26. In a typewriting machine, the combination of a support, a platen carriage mounted therein, type bars mounted in the 50 support, a foldable key action comprising levers having pivoted key-supporting arms foldable toward the platen carriage and arms connected with the type bars and having the same pivotal point as the key-supporting arms and operable by the key-supporting arms when in unfolded position, 55 said key-supporting arms being of different lengths to support the keys in banks and the groups of arms operated by the respec- 80
- tive banks of key-supporting arms also being of different lengths. 85
27. In a typewriting machine, the combination of type bars, and a keyboard comprising foldable two-part levers, the parts of each lever being pivotally connected together to operate in unison in one position only, and means positively and operatively connecting the levers with the type bars. 90
28. In a typewriting machine, the combination of a frame, type bars mounted in the frame, arms pivotally mounted in the frame and adapted to move the type bars, key-supporting arms of different lengths arranged in groups supporting keys in banks and having a common pivotal point, a knuckle 70 joint connection between each key-supporting arm and its coöperating type-bar-moving arm to adapt each pair of coöperating arms to be operated in unison in one direction and to fold relatively to each other 75 when moved in another direction. 80
29. In a typewriting machine, the combination of a frame, a platen carriage supported therein, type bars supported in the frame, a foldable support, keys foldable 85 with said support, means for pivotally supporting the keys in banks having a common fulcrum coincident with the point of fold of the support, and a non-separable foldable operating connection between each type bar 90 and its associated pivotal key-supporting means. 95
30. In a typewriting machine, the combination of a frame, a platen carriage supported therein, type bars supported in the frame, a foldable support, keys foldable 100 with said support, means for pivotally supporting the keys in banks having a common fulcrum, and a foldable non-separable operating connection between each key-supporting means and its associated type bar to permit the keys and key-supporting means to fold with said support toward the platen carriage. 105
31. In a typewriting machine, the combination of a foldable support, a platen, type bars maintained in coöperative relation to the platen, keys movable with said support into compact relation with the type bars means pivotally supporting the keys in 110 banks and having a common fulcrum, and foldable operating means forming a positive mechanical connection between each type bar and its associated pivoted key-supporting means in all positions of the keys. 115

This specification signed this first day of December, A. D. 1915.

BENJAMIN W. TUCKER.
